UNITED STATES PATENT OFFICE.

JOHN CUNNINGHAM, OF WILKES-BARRE, PENNSYLVANIA.

DARNING-BULB.

1,261,491.

Specification of Letters Patent.

Patented Apr. 2, 1918.

Application filed December 17, 1917. Serial No. 207,605.

To all whom it may concern:

Be it known that I, JOHN CUNNINGHAM, a citizen of the United States, residing at Wilkes-Barre, in the county of Luzerne and State of Pennsylvania, have invented certain new and useful Improvements in Darning-Bulbs, of which the following is a specification.

This invention relates to darning bulbs and the object thereof is to provide a bulb of this character so constructed that breakage of the needle is prevented and a neat, smooth darn insured which may be accomplished in much less time than with the old style wooden darning bulbs.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a longitudinal section of a bulb constructed in accordance with this invention,

Fig. 2 is a front end elevation thereof, and Fig. 3 is a detail partly in section showing a slightly different form of the invention.

In the embodiment illustrated, a bulb 1 is shown spherical in shape, although obviously it may be ovate if found desirable and which is composed of two hollow sections 2 and 3, the inner section 3 being constructed preferably of rigid material, such as metal or the like, and having a handle 4 fixed thereto, said handle being here shown made integral therewith. This handle 4 may be of any desired construction. The section 3 is provided at its free edge around the perimeter thereof with a groove 5 on its inner face which is designed to receive an annular bead 6 carried by the edge of section 2 on its outer face so that when assembled these two sections will have a clencher-like joint connecting them, similar to that used for connecting a clencher tire to a vehicle wheel.

The section 2 is composed of any soft springy material preferably of rubber sufficiently hard to retain its shape during the

darning operation and yet yieldable enough to permit it to conform to the shape of the object being darned. This section has an aperture 7 therein to prevent its remaining in collapsed position when an indentation has been made therein. It will thus be seen that by so constructing this bulb, the section 2 will be presented to the article to be darned and the needle used for darning will not have its point broken by contact with a hard object of which the bulbs now in use are constructed and which is a great objection thereto. Moreover, by making this section 2 of yieldable material, it will conform to the shape of the object being darned and thereby insure a smooth, even darning of the hole in the sock or other article being darned.

In Fig. 3 a slightly different form of the invention is shown, the lower section 3' of the bulb being shown made of solid material and the handle 4' being detachably connected therewith, having a reduced threaded extension 8 at its inner end which is designed to engage a correspondingly threaded socket in section 3' and has a shoulder 9 at the base of said extension against which the section 3' abuts when the parts are in assembled position.

A head 10 is preferably formed at the outer free end of the handle of the bulb to assist the operator in holding the bulb in adjusted position, preventing slipping off of the hand from its end of the device.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

1. A darning bulb composed of two semi-spherical hollow sections, one having a groove on its inner face adjacent the edge thereof and the other a bead on its outer face for interlocking engagement with the groove of the other section, one of said sections being composed of yieldable shape re-

taining material having a smooth outer surface.

2. A darning bulb composed of semi-spherical sections having coöperating means at their abutting edges for interlocking engagement to detachably connect the sections, one of said sections having a handle extending radially therefrom, and the other section

composed of yieldable material and having an aperture therein.

In testimony whereof I affix my signature in presence of two witnesses.

JOHN CUNNINGHAM.
